UNITED STATES PATENT OFFICE.

OTTO WINTERMEYER, OF LEVERKUSEN, NEAR COLOGNE, GERMANY, ASSIGNOR TO
FARBENFABRIKEN VON FRIEDR. BAYER & CO., OF ELBERFELD, GERMANY, A
CORPORATION OF GERMANY.

APPARATUS FOR THE MANUFACTURE OF PHOTOGRAPHIC FILMS.

1,022,617.

Specification of Letters Patent.

Patented Apr. 9, 1912.

Application filed October 22, 1909. Serial No. 524,000.

To all whom it may concern:

Be it known that I, OTTO WINTERMEYER, citizen of the German Empire, residing at Leverkusen, near Cologne, Germany, have 5 invented new and useful Improvements in Apparatus for the Manufacture of Photographic Films, of which the following is a specification.

My invention relates to new and useful 10 improvements in machines or apparatus for the manufacture of photographic films, and more particularly to machines for making or forming the strip or sheet of composition material, such for instance as celluloid, which 15 acts as the carrier or support for the sensitized emulsion.

The object of the invention is to provide a 20 machine for the purpose set forth which will be simple in construction, efficient in operation and which will permit of the formation of a continuous strip or sheet of the film from a batch or batches of raw material subjected to the machine.

The invention consists in the improved 25 machine to be fully described hereinafter and the novelty of which will be particularly pointed out and distinctly claimed.

I have fully and clearly illustrated my 30 invention in the accompanying drawings to be taken as a part of this specification and wherein—

Figure 1 is a view in side elevation and partly in section of a machine embodying my present invention. Fig. 2 is a view in 35 side elevation of the opposite side of the machine from that shown in Fig. 1, the drying casing being shown in longitudinal section. Fig. 3 is a sectional view on the line 3—3 of Fig. 2.

Referring to the drawings by characters of reference—A designates generally a drum constructed of a pair of annular elements 1, 1 spaced apart from each other and preferably formed of bar metal which is I-shaped 45 in cross-section. Secured to the internal flanges of these annular elements is a continuous strip of sheet metal 2 or other suitable material, which forms the periphery of the drum and closes the circumferential space between the said annular elements, the inner face of this shell forming the surface upon which the film is formed. The size of the drum and the width of the strip 2 are

immaterial but are usually proportioned according to the width and length of the 55 film to be made, and, of course, it will be understood that the inner face of the shell is made smooth and unbroken in order that the film when cast or formed will have a smooth and unblemished surface. 60

Suitable means is provided for revolving the drum on its longitudinal axis, said means consisting preferably of spaced bearing rollers 3, 3 mounted upon shafts 4, 4, the latter being journaled in the upper ends 65 of standards 5, 5, said rollers 3, 3, having circumferential flanges 6, 6. The drum rests and is revoluble upon the rollers 3, 3 and is arranged so that the outer heads or flanges of the bars 1, 1 rest upon the peripheries of said rollers, the flanges on the latter serving to engage the said bars and prevent lateral dislodgment of the drum from the rollers during the revolution of the drum. The drum is revolved by driving one of the 75 rollers 3, 3 in any suitable manner, one of the shafts 5, 5 being provided with a pulley 7, or other transmission mechanism.

Mounted upon suitable vertical standards 8, 8 is a hood which envelops the shell of the 80 drum throughout the greater portion of its circumference, said hood comprising a circumferential portion or wall 9 arranged outside of the drum, but spaced therefrom and depending skirt portions 10, 10 which project 85 inwardly toward the axis of revolution of the drum a sufficient distance to completely cover the shell of the drum and terminate at a point between the said shell and the center of the drum. The ends of this hood terminate at a point below the horizontal diameter of the drum so that the great portion 90 of the shell of the drum is enveloped by the hood and said skirt portions are connected within the shell by a plate or partition 11 so 95 that a portion of the shell is included within a tubular chamber to which air may be supplied through the opening 12 and find exit therefrom through the opening 13.

Suitable means is provided for heating 100 the drum, and, while a number of expedients can be employed for this purpose, I prefer to use the construction which I will now describe.

Located in the space between the part 9 105 of the hood and the outer surface of the

drum, and preferably down between the outer projecting parts of the bars 1, 1 is a heating coil of pipe 14 the legs of which extend transversely of the periphery of the drum. Any heating medium may be caused to circulate through the heating coil, such as steam, and it will be seen that the coil heats the air within the hood, and also heats the shell of the drum.

- 10 In this invention it is proposed to form the film upon the inner surface of the shell of the drum during the revolution of the latter, and means is provided for feeding the composition of matter to the drum and distributing it upon the shell during the revolution of the drum. While various means might be devised for accomplishing this step, I prefer to employ a feed ladle or trough 15 located within the drum adjacent 15 the bottom portion thereof, and extending transversely of the shell, said trough being pivotally supported on suitable bracket arms 20 secured to standards 17 arranged on opposite sides of the drum, said trough being 25 so supported on said brackets that the composition may spread therefrom upon the inner surface of the shell.

In operation the batch spreads upon the inner surface of the shell from the feed 30 trough 15 and the shell revolving in the direction of the arrow, as shown in Fig. 1, continuously carries the batch up within the hood, the batch, owing to the movement of the drum, spreading and flowing into a thin, 35 film. As the film moves up within the hood the air flowing therethrough and the heat supplied from the heating coil, evaporate the more volatile constituents of the composition and leave the finished film upon the 40 shell.

Means is provided for continuously removing the finished film from the shell, and this means may consist of a receiving spool or reel 19 supported on a horizontal axis 45 within the shell, said spool being provided with a gudgeon 20 journaled in a bearing 21 at the upper end of a standard 22. Any suitable means is provided for turning the spool or reel as a hand crank 23 connected to 50 said gudgeon.

Mounted in the upper ends of the standards 17 is a horizontally disposed roller 24 extending through the drum transversely of the latter, and with its periphery closely adjacent the inner surface of the drum shell. When the film-forming process is being carried on, the batch being deposited on the shell, is formed into a film as above described, and the portion first formed moves 55 around beneath the roller 24, when it is detached from the shell and carried up and attached to the reel 19, upon which each sheet of film may be wound as it is formed.

60 Among the advantages of the above construction the following may be mentioned:

It will be seen that by forming the film on the inside of the drum a compact apparatus may be provided for the reason that the feeding device for the composition may be located within the confines of the drum at the bottom thereof instead of being located exterior to the drum and above the same, as would be the case were the film formed in the exterior of the drum. This is of advantage for the reason that the height of the machine is reduced. The apparatus also provides simple and effective means for heating the shell and the film thereon, so that the heat is brought into intimate contact with the film while being formed to thoroughly evaporate the volatile substances therefrom. It will also be apparent that the film is formed continuously, its length depending solely upon a continuous feed of the film composition, and the number of revolutions the shell or drum is permitted to make.

What I claim and desire to secure by Letters Patent of the United States is:—

1. A machine for forming film comprising a revoluble shell having an internal continuous film-forming surface and open ends, means for heating the shell, means for depositing material upon said surface, and a chamber through which the shell revolves and inclosing said heating means.

2. A machine for forming film comprising a revoluble shell having an internal continuous film-forming surface and open ends, means for depositing material upon said surface, a chamber through which a portion of the circumference of the shell moves, and a heating coil in the chamber exterior of the shell.

3. A machine for forming film comprising a revoluble shell having an internal continuous film-forming surface and open ends, means for heating the shell, means for depositing material upon said surface, a chamber inclosing a portion of said shell and the heating means, and means for permitting a circulation of air through the chamber.

4. A machine for forming film comprising a revoluble shell having a continuous internal film-forming surface, means for continuously depositing material upon said surface, and means for continuously stripping completed film therefrom during the revolution of said shell.

5. A machine for forming film comprising a revoluble shell having a continuous internal film-forming surface, means for depositing material upon said surface, means for drying the film on said surface during the revolution of the shell, and means for stripping film from the surface.

6. A machine for forming film comprising a revoluble shell having a continuous internal film-forming surface, means for depositing material upon said surface, means

for drying the film, a stripping roller adjacent the surface for removing the film from the shell, and a reel for receiving the stripped film, said depositing means, roller, and reel being operable within said shell.

7. A machine for forming film comprising a revoluble shell open at its ends and having an internal film-forming surface, rollers upon which said shell is supported and revolves, means at the bottom of the shell for depositing material on said surface, a drying chamber inclosing the upper portion of the shell, a stripping roller adjacent and in advance of the depositing

means, and a reel projecting within the shell 15 for receiving the stripped film.

8. A machine for forming film, comprising a revoluble shell having a continuous internal film forming surface, and means for stripping the completed film therefrom. 20

In testimony whereof I have hereunto set my hand in the presence of two subscribing witnesses.
